BRAIDING MACHINE

Wiliard W. Bardsley, Providence, R. I., assignor
to Wardwell Braiding Machine Company, Cen-
tral Falls, R. I., a corporation of Maine

Application July 5, 1935, Serial No. 29,803

7 Claims. (Cl. 96—5)

This invention relates to braiding machines and particularly to braiders of the so-called "flat" type wherein two sets of yarn supplies are traveled in opposite directions about a common axis with the strands leading therefrom to a central braiding point where they are enmeshed in a tubular or like fabric.

One object of the invention is to provide a braiding machine of the type indicated having means for establishing the braiding point in proper relation to the direction of feed of the yarns to prevent the braiding strands from riding upward in the direction of feed of the braided material.

Another object of the invention is to provide means for preventing the braiding point from becoming so located with respect to the supplies of yarn as to prevent the strands from one set of supplies from being passed under or around the supplies of the other set.

Another object of the invention is to provide controlling means for maintaining the braiding angle of the strands substantially constant to produce a more uniform braid.

Another object of the invention is to provide means for manipulating the braiding strands at intervals during their passage into the fabric to avoid chafing the yarns and also to prevent knots or other enlargements in the yarns from catching and dragging at the crossing points of the strands.

Another object of the invention is to provide strand-controlling means of the type specified particularly for use in braiding machines wherein the supply packages revolve in orbits at substantially the same level and the strands lead to the braid at substantially right-angles to the direction of feed of the fabric.

Another object of the invention is to provide an improved vibratory manipulating means for the strands to clear them where they cross and means operated from the basic machine to actuate said manipulating means at a location above the braiding mechanism.

Further objects of the invention are set forth in the following specification which describes a certain type of braiding machine embodying the present device or apparatus.

The invention is illustrated by way of example in the accompanying drawings wherein:

Fig. 1 is a vertical sectional view through a braiding machine embodying the present invention;

Fig. 2 is an enlarged detailed view of the strand-manipulating device shown partly in section on its vertical axis.

Fig. 3 is a similar view showing the strand-manipulator elements in a different position from that illustrated in Fig. 2;

Fig. 4 is an inverted plan view of the strand-manipulator showing the relationship of the crossing strands thereto as they lead to the braid;

Fig. 5 is a similar view showing the crossings of the strands as advanced toward the braiding point; and

Fig. 6 is a similar view showing the crossings of the strands in a still further advanced position with respect to the axis of the manipulator.

The invention is herein shown as applied to a high-speed braiding machine of circular type wherein the supplies of yarn are revolved in concentric orbits and the strands from one set of supplies controlled to pass them over and under the supplies of the other set to perform the braiding operation. In machines of this type the yarn supplies are sometimes arranged in two sets or groups with the supply bobbins, cops or packages of one set disposed with their axes directed toward the braiding point and the bobbins or supplies of the other set arranged in a circle therebelow; means being provided for revolving the two sets of supplies in opposite directions and manipulating the strands from the lower set of supplies to cause them to pass over and under the upper supplies. In the machine as herein shown, however, the two sets of supply bobbins, cops or packages are arranged in inner and outer series with the yarn packages of the inner set disposed with their axes in a horizontal plane while the bobbins or yarn packages of the outer set of supplies have their axes vertically disposed.

This latter disposition of the yarn supplies is not essential to secure the benefits of the present invention, although the invention is especially adapted for machines of the flat type wherein the yarn supplies are grouped in inner and outer sets and the strands therefrom lead to the braiding fabric in a direction generally perpendicular to the direction of feed of the braid.

Referring first to Fig. 1 of the drawings, the braiding machine as herein shown comprises a base 2, which may be supported on a frame or rest upon a bench or table, and a plurality of generally circular heads or turrets 4 and 5 mounted on the base to rotate in opposite directions about the axis of the machine. The base 2 is of substantially bowl shape with its inner cavity 3 providing an oil-reservoir for the gearing and other moving parts. Rising from the center of the floor of the base 2 is a hollow standard 6 of inverted funnel-shape which serves as a station-

ary mounting for an upper tubular post 7 which supports a central thrust-bearing for one of the rotating heads of the machine. The tubular post 7 has a circumferential flange 8 at its lower end 5 secured to the upper rim of the standard 6 by means of screws 9. The upper end of the post 7 is closed by a dome-shaped cap or closure 10 formed with a central opening 16 and having a reduced portion fitted within the bore of the 10 post.

Mounted on the outer circumferential rim 11 of the base 2 is a fixed bearing-race 12 formed with a concaved groove 13 for receiving suitable balls 14 which support the outer turret or head 4 15 of the machine. The outer head 4, sometimes referred to as the track-plate, is substantially dish-shaped in cross-section comprising a flat annular bottom portion 15, from which rises a flaring bowl-like wall 20. To the under side of the annulus 15 of the head 4 is fastened a ball-race 21 disposed opposite to and of the same form as the lower fixed face 12, previously referred to. The balls 14 roll in the opposite races to provide a friction-reducing bearing for the head 4 supported therefrom. Fast on the upper side of the flat annulus 15 of the head 4 is a third ball-race 22 for receiving the balls 23 of a bearing for supporting the inner turret or head 5. The balls 23 revolve in an upper race 24 fastened to the under 30 side of a flat annular wall 25 of the head 5.

The inner head 5 is also substantially dish-shaped as comprising a central flat annular portion 26 with an inclined wall rising therefrom and merging into the previously-mentioned flat 35 annular portion 25. From the annulus 25 the flaring wall rises again in substantially parallel relation to the dished wall 20 of the outer head 4.

The outer turret or head 4 carries the yarn bobbins or supplies S of the outer set to revolve them in a circular orbit concentric with the axis 40 of the machine. It also carries a circular track or guideway 30 around which the carriers for the other inner set of supplies S' are traveled in the opposite direction about the axis of the machine. The outer supplies S, shown by dot-and-dash 45 lines in Fig. 1 of the drawings, are represented as cylindrical cross-wound packages of well known type, but they may be of any other form. The yarn packages are wound on axial cores or tubes t and carried by supply-holders, indicated generally 50 at 37, which are rotatably mounted on spindles 31 supported from brackets 32 overhanging the rim of the outer head 4. As herein shown the brackets 55 32 are of substantially L-shaped with vertical arms 33 arched at the top and provided with feet 34 seated on and secured to the upper face of the track 30 on the head 4 by suitable means such as the screws 35. Suitable means such as ratchet-paws or friction brakes are provided for engagement 60 with brake-disks 36 on the supply-holders 37 to control the rotation of the packages S to pay off the strands y of yarn therefrom; such devices being well known to those versed in the art and therefore not herein shown or described in detail. At one side of the brackets 32 are 65 standards 38 provided with guide-eyes 39 through which the strands y pass after drawing through the tension-devices, not herein shown.

The inner bobbins or supply-packages S' are 70 mounted on shuttle-like carriers 40 which slide on the track or guideway 30. For this purpose the track 30 may be formed with a V-shaped groove 41 which is provided with a slot or keyway 42 on its under side. The carriers 40 are of generally 75 lenticular contour or boat-shaped, in accordance

with the usual practice, to adapt the strands y to slide along their edges either over or under the supply-packages S' carried thereon. Each carrier 40 has a tapered keel or runner 43 fitted to slide in the groove 41 of the track 30 and provided 5 with a spline or feather 44 for engaging the slot 42 therein to retain the carrier in place. The track or guideway 30 is of annular or circular shape and substantially continuous around the machine, being divided into sections with radial slits 49 10 between the sections which are shown in Fig. 1 as the portions without cross-hatching. In other words, vertically-extending slits are provided at intervals of the circumference of the track 30 15 wherein the strands of yarn may play up and down as they pass under or over the carriers 40 and the supply-packages S' carried thereby.

The inner supply-packages S' are mounted on supply-holders of the same type as those for the outer supplies, being indicated generally at 45 in Fig. 1 of the drawings. The holders 45 are rotatable on horizontal spindles 46 and carry 20 brake-disks 47 engaged by pawls or the like operated from suitable tension devices not herein shown. After passing through the tension devices 25 the yarns draw through guide-eyes 48 and lead therefrom directly to the braiding point in a substantially horizontal plane.

The yarns y from the outer supply packages S are manipulated to pass them alternately over and under the carriers 40, either singly or in pairs in accordance with the pattern of the braid desired, by means of stationary deflectors 50 of the type shown and described in U. S. Letters Patent to Miller No. 1,602,442, dated October 12, 1926. The deflectors 50 are herein illustrated as consisting of standards or brackets supported from the base 2 of the machine and having suitable cross-arms 51 at the top along which the strands slide to deflect them above 40 the pointed ends of the carriers 40 so as to cause them to ride along the curved edges thereof above the inner supply packages S'. Normally, the strands y from the outer supplies S move in a course which causes them to engage under the 45 points of the carriers 40 so that they will pass under the inner supplies S' at points where deflectors are not provided. In this way the strands y from the outer supplies S are caused to pass over and under the inner supplies S' to 50 enmesh them with the strands y' to form the braided fabric indicated at B.

The shuttles or carriers 40 for the inner supplies S' are propelled around the track 30 by means of driver-bars 52 which are slidably 55 mounted in radial slots 53 in the outer rim of the inner turret or head 5. The driver-bars 52 are arranged in pairs and held in place in the slots 53 by the inclined wall 54 of a cover-plate 55 extending horizontally across the central part 60 of the machine. As herein shown the cover-plate 55 is connected rotatively with the head 5 by means of studs 56 mounted in bosses 57 on the head with their tapered ends engaging in the bores of bosses 58 on the under side of the 65 cover-plate. Each carrier 40 has a pair of slots indicated at 59 with which the ends of a pair of driver-bars 52 engage, the bars of each pair being reciprocated in their slots 53 as the carriers travel around the machine in such manner as 70 to disengage first one and then the other from the carrier to prevent interference with the strand as it draws under the carrier.

The driver-bars 52 are reciprocated by means of a cam 60 having an undulatory groove 61 en- 75

gaging with rollers 62 journaled on pins 63 projecting from the under side of the bars. The cam 60 is of saucer-shape in conformation with the inclined wall 20 of the outer head 4, to 5 which it is attached by suitable means such as screws 64. It will be understood that as the carriers 40 are propelled around the track 30 by the rotation of the inner head 5 carrying the driver-bars 52, the cam 60 is rotated in the opposite direction with the head 4 to cause the cam-groove 61 to oscillate the driver-bars 52 to alternately engage them with and disengage them from the carriers as the strands y pass thereunder.

15 The two turrets or heads 4 and 5 are rotatively driven by means of suitable gearing connected to a drive-shaft 65. The drive-shaft 65 is journaled in suitable bearings 66 formed integral with or attached to the base 2 of the machine 20 as herein shown. The shaft 65 may be driven from a pulley 67 connected thereto by a clutch 68 operated from suitable starting and stopping mechanism not herein shown and described. On the inner end of the drive-shaft 65 is a bevel 25 gear 70 having its teeth in mesh with a ring-gear 71 which is riveted or otherwise secured to a depending flange 72 on the annular portion 15 of the outer turret or head 4. A similar ring-gear 73 is riveted or otherwise suitably attached to the rim of an annular flange or skirt 74 secured to the lower flat annular portion 26 of the inner head 5 at 69. It will thus be observed that as the gear 70 is rotated with the drive-shaft 65 it will transmit motion through 30 the ring-gears 71 and 73 to rotate the heads 4 and 5 in opposite directions. The upward thrust of the geared drive is taken by a thrust bearing 75 which has a hub 76 surrounding the central post 7 with feet 77 resting against the upper 35 face of the flat annular portion 26 of the head 5. The thrust bearing 75 is held in place by means of an adjustable collar 78 screwed onto a threaded portion of the post 7 and formed with a split portion having a screw 79 extending therethrough to bind it on the threads to lock it in position.

The mechanism of the braiding machine so far described is similar in general to other machines of the same type and the strand-controlling device of the present invention is applied thereto in the manner as next explained. At the opposite side of the axis of the machine 40 from the drive-shaft 65 the base 2 is formed with an opening 80 for receiving a bearing member 81 similar to the bearing 66 for the drive-shaft. The bearing member 81 is flanged to fit within the opening 80 in the base 2 and has a downwardly-extending portion abutting the side of the base with a tubular portion 83 projecting horizontally outward therefrom. Journaled in end bearings in the member 81 is a shaft 85 extending coaxially with the drive-shaft 65. At the inner end of the shaft 85 is a bevel pinion 86 meshing with the ring-gears 71 and 73 on the heads 4 and 5 to cause it to be driven therefrom. At the outer end of the shaft 85 is a smaller beveled gear 87 which meshes with a similar gear 88 fast on a vertical shaft 90. The vertical shaft 90 is supported in a bearing 91 45 formed as a part of an upright bracket or standard 92 having a ring-like split hub-portion 96 surrounding the outer end of the bearing-member 81 and clamped thereto by means of a binder-screw indicated at 93. The lower end of the bracket or standard 92 is shaped to form a hous-

ing for the gears 87 and 88, a cover 94 being fastened thereto by screws 95 to provide a complete enclosure for the gears. The upper end of the shaft 90 is journaled in a bearing 98 fitting the bore of a split hub-portion 99 of the standard 92 and clamped therein in the same manner as the lower hub 96 of the standard is clamped to the bearing member 81. Connected to the bearing 98 by a web 101 is a bearing 100 formed as part of a horizontal arm or strut 103. The arm 103 is formed with a split hub 104 at its end which is clamped around a bearing 105 carrying a shell or housing 110 for the parts of the strand-manipulator to be later described.

10 Journaled in the bearings 100 and 105 is a horizontal drive-shaft 106 for actuating the strand-controlling device. The shaft 106 is driven from the vertical shaft 90 by means of a pair of intermeshing bevel gears 107 and 108 which are enclosed in the housing formed by the web 101 connecting the standard 92 and arm 103; a cover 109 being fitted thereto. It will be observed that as the heads 4 and 5 of the machine are driven from the drive-shaft 65 the auxiliary shaft 25 will be rotated by the gear 86 to drive the vertical shaft 90 and thereby the horizontal drive-shaft 106 for the strand-manipulating device.

15 Referring now more particularly to Figs. 2 and 3, the strand-manipulator comprises a plurality of annular elements arranged above and coaxially of the braiding mechanism to adapt the fabric to pass therethrough as it is braided from the strands y and y' delivering from the revolving supply packages S and S'. The present machine 20 may be employed for braiding a tubular fabric without an inner core or it may be used for covering a core, for example, wire or other forms of electrical conductors. In the present drawings the machine is illustrated as operating to 25 braid a fabric covering around a core C fed axially through the machine by suitable means not herein shown. The core C is delivered from a reel or other supply-holder disposed beneath the machine and drawn up through the base 2 and hollow post 7 to feed through the opening 16 in the dome 10. The core C may be fed through the machine by means of the usual take-up device 30 consisting of a rotating capstan or grooved wheel arranged above; these parts not being herein shown or described as they may be of any usual arrangement.

35 Surmounting the dome 10 at the axial center of the braiding machine is the cylindrical casting or shell 110, previously mentioned as carried by the bearing 105 supported at the inner end of the horizontal arm or strut 103. At the upper end of the shell 110 is a split hub 111, in the bore of which is mounted a tubular quill 112 forming a channel or passage through which the 40 braided material feeds. The quill or tube 112 is adjustable vertically in the hub 111 and adapted to be secured in its adjusted position by tightening a binder screw 114, shown by dotted lines in Fig. 2 of the drawings, which extends through the split portion of the hub. The lower end of the shell or casing 110 is of hemispherical form provided with a central opening 113 to which is fitted a hardened metal thimble or ring 115. The lower rim of the ring 115 is disposed in the horizontal plane of the axes of the inner supply packages S' to provide a locating annulus for the strands to pass through whereby to direct them to the braiding fabric at a definite angle with respect to the direction of feed of the strands. The 45

inner quill or tube 112 projects partly through the locating ring or annulus 115 with its lower rim positioned slightly raised above the lower rim of the annulus and spaced inwardly therefrom. The strands y and y' leading respectively from the outer and inner supply packages S and S' draw across the lower rim of the annulus 115 and thence upwardly across the rim of the quill 112, whence they pass into the braid in crossed relationship; it having been previously noted that the quill 112 is vertically adjustable in its supporting hub to regulate the relation of its lower rim to the rim of the annulus 115.

Slidably mounted on the periphery of the tube 15 or quill 112 is a third annular member or sleeve 118 which is adapted to oscillate in the space between the exterior of the quill and the interior of the annulus 115. Reciprocating motion is imparted to the sleeve 118 during the continuous rotation of the shaft 106 through the means of an eccentric connection therebetween. As shown in Figs. 1, 2 and 3, the shaft 106 carries an eccentric-disk 120 secured fast to its end. Surrounding the eccentric-disk 120 is a strap 121 carrying a link 25 or pitman 122 connected to a pin 123 projecting from the upper end of the sleeve 118. As the shaft 106 is rotated the eccentrically-operated pitman 122 actuates the sleeve 118 with a vertical reciprocatory motion to alternately raise and lower its lower rim with respect to the rims of the fixed inner quill 112 and outer ring or annulus 115. The purpose of this reciprocatory motion of the sliding sleeve 118 is set forth in connection with the following explanation of the method of 30 operation of the complete machine.

The braiding machine may be adapted for braiding any suitable number of strands in accordance with the character of fabric to be produced. To prepare the machine for operation a suitable number of supply packages S and S' are placed on the outer and inner supply-holders 37 and 45, respectively, with the strands y and y' passing through the tension devices and the guides 39 and 48. When a core is to be covered, such as the wire indicated at C in Fig. 1, it is drawn up through the center of the machine and attached to the capstan, not shown, to be fed thereby through the machine during the braiding operation. The ends of the strands y and y' are drawn toward the axis of the machine and attached to the wire or the cord C by winding them therearound.

Power is applied to operate the machine by means of a belt passed over the pulley 67 and connected with a suitable source of power such as an electric motor. To start the machine the pulley 67 is shifted into connection with the clutch 68 to effect rotation of the drive-shaft 65. The gear 70 on the shaft 65 is thereby caused to drive the ring gears 71 and 73 to rotate the heads 4 and 5 in opposite directions. The two opposite sets of supply-carriers S and S' will thus be revolved about the machine in opposite directions, the outer set of supplies being carried directly on the outer head 4 while the inner supplies S' are carried on the carriers 40 sliding in the groove 41 of the circular track 30 which is divided into sections as previously explained. The carriers 40 are slid on the track 30 by the engagement of the driver-bars 52 therewith, the bars being carried by the inner head 5 and reciprocated in the grooves 53 through their connection with the cam 60. As the supplies S revolve in the outer orbit 75 the strands y leading from the guides 39 are nor-

mally caused to pass under the pointed ends of the carriers 40 to slide along the lenticular edges on the under side thereof. As the strands slide under the carriers 40, first one and then the other of the pairs of driver-bars 52 is disengaged from each carrier to allow the strands to pass. When the strands meet the inclined edges of the deflectors 50 they are caused to ride up above the pointed ends of certain carriers to pass them above the supply-packages S' carried thereby and in this way the strands y from the outer supplies are passed alternately over and under the strands y' from the inner supplies S' to effect the braiding operation. As the core C feeds upwardly through the machine the strands y and y' draw across the lower rim of the outer fixed annulus 115 and thence across the lower rim of the inner annulus or quill 112; the relationship between these elements being such that the strands feed into the braid under guidance to restrain the braiding point from rising and to properly position the yarns in the fabric.

As the machine thus operates to braid a tubular fabric the strand-manipulator is actuated in the manner as next explained. In general, the strand-manipulator is similar to that disclosed in my prior U. S. Letters Patent No. 1,968,240 of July 31, 1934, it being noted, however, that in the device of the patent the strands are braided around a central mandrel and the braid pushed off therefrom by means of a reciprocating element actuated in consonance with a reciprocating annulus which lifts or raises the strands to free them from a fixed annulus. In the present invention the reciprocating sleeve 118 acts to press the strands downwardly to free them from the outer fixed annulus 115 as the crossing points in the strands approach and pass by the latter. The reciprocating annulus 118 is then raised above the strands again to prevent the crosses from contacting therewith; it being noted that each of the annuli has a convexed or rounded rim presenting a minimum extent of surface for contact with the strands. Then as the crosses pass the rim of the reciprocating annulus 118 without contact therewith and approach the rim of the inner fixed annulus or quill 112 the sleeve 118 is again moved downwardly to disengage the crossing points of the strands from the inner annulus. In other words the reciprocating sleeve 118 is operated at a rapid rate and in timed synchronism with the braiding operation to alternately depress the crossing strands away from first the outer annulus 115 and then the inner annulus 112.

As before indicated, the strand-manipulator is actuated from the braiding mechanism, the gear 86 being driven from the ring-gears 71 and 73 on the heads 4 and 5, respectively. The gear 86 is fast on and rotates the shaft 85 which, in turn, drives the vertical shaft 90 through the gears 87 and 88. The vertical shaft 90 transmits rotation through the gears 107 and 108 to drive the upper horizontal shaft 106 which carries the eccentric disk 120. The eccentric 120 is thus rotated to oscillate the pitman 122 to reciprocate the sleeve 118 connected thereto; the gears being so proportioned as to cause the sleeve to move downward to the position shown in Fig. 3 just before the crossing points in the yarns meet the rims of the outer stationary annulus 115 and inner annulus 112.

The action of the strand-manipulator will best be understood by reference to Figs. 2 and 3 of 75

the present drawings taken in connection with the more or less diagrammatic views, Figs. 4 to 6, inclusive. Fig. 2 illustrates the reciprocating sleeve 118, which for convenience may be termed 5 the pusher, in raised position in relation to the lower rims of the fixed annuli 115 and 112. At this stage in the operation of the braiding machine the strands *y* and *y'* cross each other at points *x* outwardly beyond the rim of the annulus 115, as indicated in Fig. 4. Now, as the pusher 118 is carried downwardly to the position shown in Fig. 3 the strands are pressed away from the annulus 115 so that the crosses *x* may pass thereby without hindrance. Then, as the crossing 10 points *x* in the strands advance toward the rim of the pusher 118 as shown in Fig. 5 the pusher is withdrawn upwardly to allow free passage of the crosses across its rim in the manner indicated in Fig. 6 of the drawings. The strands will then 15 contact once more with the lower rims of the outer fixed annulus 115 and inner fixed annulus 112, but as the crosses *x* in the strands approach the inner annulus the pusher descends again to relieve the contact of the strands with the rim 20 of the latter so as to avoid any impedance to their passage into the braiding fabric. In this way the passage of the strands into the fabric is made much easier and freer and any knots or enlargements occurring on the yarns are prevented 25 from catching to impede their progress into the braid to cause irregularities and faults in the fabric. It will be understood that the reciprocation of the pusher 118 is very rapid so that the strands have only a relatively short 30 period of contact with the rims of the several annuli; that is, they touch lightly first on the fixed annuli 115 and 112, as shown in Fig. 2, are then pressed downwardly away therefrom by the rim of the pusher 118 and then released from 35 the latter to again contact with the fixed annuli, and so on in rapid repetition. The strands are thus kept practically continuously in motion with a vibratory action which clears the crosses from the several annuli to prevent any hindrance 40 thereto in their progress into the fabric.

Particularly important is the provision of 45 means for determining the braiding point at which the strands enmesh in the fabric. Without such provision the braiding point would tend to move upwardly in the direction of feed of the braided fabric so that the strands from the outer set of supplies *S* could not be passed under the carriers for the inner supplies *S'*. Stated another way, the yarns would lead upwardly at such a 50 sharp angle to the axis of the machine that the strands from the outer set could not be deflected under the supplies *S'* and properly enmeshed in the fabric.

It will be observed from the foregoing that my 55 invention provides a highly efficient machine for fabricating tubular coverings for wire and other types of cores, or for producing a tubular braid such as sleeving; the function of the strand-manipulator being to maintain the yarns leading 60 from their supplies in proper relationship both as regards the two opposite sets of strands and with respect to the braid being produced. The outer fixed annulus across the rim of which the strands draw controls the relationship of the strands as 65 those from the outer supplies pass over and under the inner supplies, thus maintaining the braiding point in a substantially mean position with respect to the raised and lowered positions of the strands *y* as they pass respectively over and under 70 the inner supplies. It may be said that this 75

establishes a "false" braiding point, as ordinarily the braiding point would tend to rise and this would cause the strands to feed into the fabric with too sharp a pitch or lead besides interfering with the passage of the strands from the outer set in under the supplies of the inner set. It is to be understood, therefore, that the establishment of the braiding point in the manner described is absolutely essential to the production of a perfect fabric and, in addition, the strand-manipulator is essential in order that the crosses in the strands may not catch and drag over the fixed elements which determine the position of the braiding point.

It is believed that the present invention is broadly new in its application of the controlling means and strand-manipulator to the present type of machine at a point above the braiding mechanism and in such relation to the supplies as to depress the yarns to free them from the controlling means. The invention also contemplates a novel arrangement of drive for the strand-manipulator connected for actuation from the braiding mechanism of the basic machine.

While the invention is herein illustrated and described as embodied in a preferred form of construction and applied to a particular type of machine, it is to be understood that various modifications may be made in the structure and arrangement of the device and in its application to use without departing from the spirit or scope of the invention. Therefore, without limiting myself in this respect, I claim:

1. In a braiding machine, the combination of a plurality of sets of supplies adapted to be traveled about the axis of the machine in concentric paths located in substantially the same horizontal plane, means for traveling said sets of supplies in opposite directions, driving mechanism for said means, a fixed annular element 35 arranged axially of the machine above the path of the supplies and so constructed and arranged as to direct the yarns from one set of supplies in a path substantially perpendicular to the axis of the machine, an annular element reciprocable 40 with respect to the fixed annular element to cause it to press the yarns downwardly to free them therefrom, means for reciprocating said second annular element, and means connected with the driving mechanism of the machine and located 45 outwardly beyond the path of travel of the supplies for actuating said reciprocating means from the driving mechanism of the machine.

2. In a braiding machine, the combination of outer and inner sets of supplies arranged in substantially the same horizontal plane, means for revolving said supplies in opposite directions about the axis of the machine, driving mechanism therefor, means for interlacing the strands from the supplies to form a braid, an annular element 60 disposed axially of the machine with its lower rim substantially in alignment with the mean path of the yarns leading from the outer supplies over and under the inner supplies, said element so constructed and arranged as to engage the 65 yarns adjacent the braiding point to maintain the yarns from the inner set of supplies in a plane substantially perpendicular to the axis of the machine, a second annular element within and concentric of the first annular element, a third 70 reciprocable annular element disposed between the outer and inner fixed elements, transmission means located outwardly beyond the path of travel of the supplies and connected to the driving mechanism of the machine and means ac- 75

tuated by said transmission means to reciprocate the third element during the braiding operation to periodically press the strands downwardly away from the fixed elements.

- 5 3. In a braiding machine, the combination of a base, driving mechanism in said base, means actuated from said driving mechanism for revolving a plurality of sets of supplies about the axis of the machine, means for manipulating the 10 strands from the outer set of supplies to pass them over and under the supplies of the inner set to interlace them in the braid, a hollow casing arranged axially above the machine, a standard extending upwardly from the base of the machine 15 and located radially outward from the path of the supplies, means on said standard to support said casing from the base of the machine, a fixed annular member in said casing across the rim of which the strands draw to establish the braiding 20 point in a plane coincident with the horizontal path of the yarns feeding from the inner set of supplies, a second reciprocable annular member disposed concentrically within the fixed member, means for reciprocating the reciprocable member, 25 and transmission elements supported by the standard outwardly beyond the path of travel of the supplies and driven from the driving mechanism in the base of the machine to actuate the reciprocating means to cause it to intermittently 30 depress the strands leading through the fixed annular member to relieve them from contact therewith.

4. In a braiding machine, the combination of a base, heads rotatable in opposite directions on the 35 base, driving means for rotating said heads, two sets of yarn supplies carried on said heads and revolvable thereby in opposite directions about the axis of the machine, means for manipulating the strands from one set of supplies to pass them 40 over and under the supplies of the other set, a standard at one side of the machine, an arm reaching inwardly from said standard above the center of the machine, a fixed annulus supported from said standard concentrically of the axis of 45 the braid, a second annulus arranged within the first annulus, a third annulus reciprocable with respect to the two fixed annuli, means for reciprocating said third annulus, shafting carried by the standard for actuating the reciprocating 50 means, and gearing connecting said shafting to be driven from the rotating heads of the machine.

5. In a braiding machine of the flat type, the combination of a base having means for supporting two sets of yarn supplies to adapt them to 55 travel at the same level in concentric orbits, means for traveling said supplies in opposite directions about the axis of the machine, driving means therefor in the base of the machine, means for manipulating the yarns from said supplies 60 to enmesh them in a braid, means to feed the braid from the machine axially thereof, an annular member supported from the base of the machine and so constructed and arranged as to adapt the yarns to draw therethrough in engagement 65 with its rim with the path of the yarns from

the inner set of supplies controlled to maintain it in a plane perpendicular to the axis of the machine, a second annular member reciprocable with respect to the first member and so constructed and arranged as to engage the yarns 5 drawing across the rim of the first member, transmission means located outwardly beyond the path of travel of the supplies and driven by the driving mechanism in the base of the machine, and means driven from said transmission 10 means to reciprocate said second annular member to periodically press the yarns downwardly away from the rim of the first member.

6. In a braiding machine of the flat type, the combination of a base, means on the base for 15 supporting two sets of yarn supplies arranged concentrically in substantially the same horizontal plane, means for traveling the two sets of supplies in opposite directions about the axis of the machine, driving mechanism therefor in the base of the machine, a standard supported from the base of the machine outwardly beyond the path of travel of the supplies, an annular member supported from said standard concentric with the axis of the machine to adapt the strands of 20 yarn to draw therethrough to regulate the braiding point, said annular member being so constructed and arranged as to engage the yarns leading from the supplies to maintain the yarns from the inner set in a plane substantially perpendicular to the axis of the machine, a second annular member arranged concentrically of and reciprocable with respect to the first member, transmission means supported from the standard and driven from the driving mechanism in the 25 base, and means actuated by said transmission means to reciprocate said second member to press the yarns downwardly to release them from the rim of the first member.

7. In a braiding machine of the flat type, the combination of a base, means mounted on the base and adapted to support two sets of yarn supplies arranged in concentric relationship in substantially the same plane, means for interlacing the strands from one set of supplies to 45 pass them over and under the supplies of the other set to enmesh them in a braid, a standard rising from the base and located outwardly beyond the path of travel of the supplies, an annulus supported from said standard concentric 50 with the axis of the machine, said annulus so constructed and arranged as to adapt the yarns from the supplies to draw therethrough and to maintain the yarns from the inner set of supplies in a plane perpendicular to the axis of the machine, a second annulus reciprocable with respect to the first annulus, means for reciprocating the second annulus to cause it to press the strands downwardly to release them from the rim of the first annulus, driving mechanism for 55 the machine, and transmission means supported from the standard and driven from the driving means of the machine to actuate the reciprocating means.
